UNITED STATES PATENT OFFICE.

GEORGE P. PRENTIS, OF WICKLIFFE, KENTUCKY, ASSIGNOR OF ONE-HALF
TO NATHANIEL L. ROGERS AND BEDFORD F. BURTON, OF SAME PLACE.

DESIGN FOR A HARNESS-BUCKLE FRAME.

SPECIFICATION forming part of Design No. 28,695, dated May 24, 1898.

Application filed April 4, 1898. Serial No. 676,468. Term of patent 14 years.

To all whom it may concern:

Be it known that I, GEORGE P. PRENTIS, a citizen of the United States, and a resident of Wickliffe, in the county of Ballard and State of Kentucky, have invented and produced a new and original Design for a Harness-Buckle Frame, of which the following is a specification, reference being had to the accompanying drawings, forming part thereof.

Figure 1 is a perspective view of a harness-buckle, showing my new design for a buckle-frame. Fig. 2 is a central longitudinal sectional view.

As shown in the drawings, the leading or material feature of my design consists in the

shape or configuration of the buckle-frame, which is formed with a flat converging front end, with outwardly-curved and outwardly-flaring rear end, having an opening, and with side plates having rounded projections at their ends.

Having thus described my invention, the following is what I claim as new therein and desire to secure by Letters Patent:

The design for a harness-buckle frame substantially as herein shown and described.

GEORGE P. PRENTIS.
